United States Patent

Des. 240,861

Patented Aug. 3, 1976

240,861

MICROSCOPE STAND

John T. Armbruster, Niagara Falls, N.Y., assignor to
American Optical Corporation, Southbridge, Mass.

Filed Feb. 18, 1976, Ser. No. 657,009

Term of patent 14 years

Int. Cl. D16—06

U.S. CL. D16—57

FIG. 3

FIG. 1

FIG. 2

FIG. 1 is an elevated front perspective view of a microscope stand;

FIG. 2 is a perspective view of the front of a microscope stand taken from below the horizontal plane; and

FIG. 3 is a fragmentary view showing the knob and one side of the body portion of the microscope stand.

I claim:

The ornamental design for a microscope stand, as shown and described.
